UNITED STATES PATENT OFFICE.

HELENE KOMUSIN, GEB. LIEDTKE, OF BERLIN, GERMANY.

ROLLING STAMP WITH COUNTING MECHANISM FOR VARIOUS PRINTING PURPOSES.

Application filed March 22, 1922. Serial No. 545,891.

To all whom it may concern:

Be it known that I, HELENE KOMUSIN, GEB. LIEDTKE, a citizen of the German Republic, residing at Berlin, Germany, have 5 invented certain new and useful Improvements in Rolling Stamps with Counting Mechanism for Various Printing Purposes, of which the following is a specification.

This invention relates to a rolling stamp 10 with counting mechanism for printing purposes of any kind without use of stamps designed for the special purpose and it comprises an arrangement for the locking of the value-stamp after the printing of a determined number of stamps or if the counting mechanism is fraudulently removed or if the counting mechanism should fail.

With the counting devices of known construction the operation of the counting 20 mechanism is, so to say, continuous, as the counting mechanisms are fitted, according to the number of the figure-compositions to be supplied, with a corresponding number of figure disks. After the largest figure 25 has been printed and registered the counting mechanism returns to the zero-position and the figure disks begin to work again. It has hitherto not been the custom to make counting mechanisms stop automatically at 30 a predetermined figure nor to limit their use to this determined figure.

This invention has for its object, to improve the construction of a counting mechanism in such a manner that, at a predetermined figure, this counting mechanism, and with the same also a driving mechanism connected with it, are stopped and locked. The figure, at which the stopping occurs is either always the same or variable.

40 In order that the invention may be clearly understood, I shall proceed to describe the same with reference to the form of construction shown by way of example on the accompanying drawing, wherein:

45 Fig. 1 is a front elevation partly in section.

Fig. 2 is a side elevation partly in section.

50 Figs. 3, 4 and 5 show constructional details and Fig. 3 is a section on line A—B of Fig. 4.

In Fig. 1 the well known arrangement of the rolling stamp is shown in dotted lines. The counting mechanism is controlled in the well known manner by the projections *a*.

55 The counting mechanism consists of the counter *b* which is moved by the engage-

ment of its driving arm *c* engaging with the fork *d* of the lever *e*. With this object in view the driving arm *c* is keyed upon the shaft *b'* of the counter. On the upper end 60 of this shaft *b'* a sleeve is mounted which has a button *y'*. At the lower end of shaft *b'* an annular disk *y''* is arranged which has a hand *y* at one side and an abutment arm *y'''* at the other side (Fig. 5). A spring *Z* 65 wound around the shaft *b'* bears with its upper end against the hub of the driving arm *c*. The spring *Z* acting upon the annular disk *y''* presses the hand *y* upon the upper edge of the counter which has two 70 indentations *b''* in which the hand *y* and arm *y'''* may move.

In the casing of the rolling stamp on the wall 1 the box 2 is fixed which is open at the bottom end and has a pivot pin *k* on the side turned away from the wall 1. A lever *e* having two arms *i* and *v* is pivotally mounted on the pin *k*. The upper end *d* of lever *e* is fork-shaped. On the inner surface of the lever an angular abutment *e'* is arranged, an angular abutment *u* projecting from the lower end of said lever. A spring *m* inserted in pivot pin *k* acts upon pin *m'* of the lever *e* and presses the lever into the initial position. At each rolling movement 80 of the printing cylinder *f* the projections *a* are moved by the toothed wheels *g* and *h* against the arm *i* which is thus raised so that it oscillates around its fulcrum *k*. This oscillation is transferred to the arm *c* which is influenced by a spring *m*, the counting mechanism being thus moved according to the number of operations of the rolling stamp. An angle lever *n* is pivotably mounted on a pin *o'* of the counter box 2 85 in front of the arm *e* and pressed against said arm by the action of a spring *o*, the right hand side arm *n* of said angle lever being raised by the projection *a* as soon as the same has left the lever arm *i* so that the left hand side arm *n'* of said angle-lever pressing upon the arm *i* pushes this arm back into its initial position.

Below the counter *b* an axle *p* is revolvably mounted. An angle lever fixed upon the right hand end of said axle *p* is pushed, owing to the action of a spring *r* attached with one end to axle *p* and with the other end to wall 1, so that its arm *q* bears against the bottom of the counter, the downwardly projecting arm *s* of said lever being in contact with an abutment *u* of an arm *v* where-

by the accidental or fraudulent depression of the lever *i* and the bringing out of engagement of the arm *e* with the fork *d* is prevented.

5 If the counting mechanism were fraudulently removed the arm *g* would loose its hold and it would consequently swing upward under the action of spring *r*. The end *s* of the lever acts thus upon the abutment of lever *e*, so that the lever *e* is swung to the left and so that its arm *v* gets into the path of the projection *a*. This projection *a* would at the continuing of the rolling movement be finally below the arm *v* and push the same with the lever *e* up to the limit of its travel, whereupon the projection *a* will be held and locked by arm *v* so that the rolling stamp is locked.

20 At the reinsertion of the counter *b* the lever *g* is pressed down by the lower surface of the counter, lever *s* being swung back in tensioning spring *r* and in releasing the abutment *u*. At the same time lever *e* is returned to the position of rest through 25 the action of spring *m* and the arm *v* is moved out of the path of the projection *a*.

25 In order to prevent the use of the rolling stamp as soon as the number disks of the counting mechanism have arrived at a pre-determined total the following arrangement is provided.

30 A disk *w* is mounted upon the upper number-disk which has pins *w'* or the like at its circumference and which revolves regularly and simultaneously with said upper number-disk. There can be any number of such pins and the distance between every two pins corresponds with a determined amount of fees or with a determined number 40 of operations of the rolling stamp. The pins are arranged in such a manner that the counting mechanism can be adjusted for a determined amount or for a determined number of revolutions of the rolling stamp.

45 Over the counter casing a hand *y* is arranged, beside the operating arm *e*, said hand being in connection with a button *y'* so that it can be adjusted by said button, a spring being provided for securing the 50 parts *y* and *y'* in the working position.

55 If during the use of the rolling stamp the upper number disks *b'''* of the counting mechanism is advanced the locking disk *w* with the pins *w'*, *w''* and so on, connected with said number-disk, participates in the rotating movement of said number disk. The pin *w'* for instance will thus strike against the hand *y* and move the same until the advance movement is at an end. The 60 lever *e* is arranged with regard to the hand *y* at such a distance that it can just pass along the corresponding pin *w'*, *w''* and so on before the feed movement is finished.

65 During the feed movement the hand *y* is pushed by the pin *w'* into the path of

lever *e* which is thus forced through the pressure of spring *m* to move back from its extreme feeding position into the initial position so that its abutment *e'* strikes against the hand *y* which stands on its path. The lever *e* is thus stopped after the arm *y''* has come in contact with the end of aperture *b''* so that the further movement of hand *y* and of disk *w* is prevented half way between the pins *w'* and *w''*. The projection *a* which acts upon the arm *i* has swung this arm completely out of its path during the rolling movement of cylinder *f* and acts now upon the angle lever *n*. The arm *n'* of this angle lever is in contact with the arm *i*. As lever *e* is stopped in almost vertical position by hand *y* the angle lever *n* cannot be freely oscillated by the projection *a*, the arm *i* being securely placed on the circular path of the arm *n'* so that the angle lever *n* prevents the passing along of the projection *a*. The printing cylinder is locked.

90 The end of the hand is situated between the pins *w* and *w'*. At a point, visible from the outside, either at the top or at the side to the casing, in proximity of the button *y'*, a scale is provided the graduations of which indicate for which amount the hand *y* is adjusted.

95 If a new rolling stamp is delivered or if a rolling stamp has been used for the printing of stamps up to the prepaid amount the clerk adjusts the hand *y* by means of the button *y'* upon the scale in accordance with the amount which is paid. If for instance L. 50.0.0 are paid the apparatus can be used until the pin *w* which corresponds for instance to the amount of L. 50.0.0 or to 1000 stampings comes in contact with the end of the hand *y*. From this moment the counting mechanism is locked and if the projection *a* acts upon the right hand side arm *n* of the angle lever, the left hand side arm of the same presses against the arm *i* which is already locked as the arm *e* which operates the counting mechanism is locked, so that the lever *e* cannot oscillate. The arm *e* is thus held on the path of the projection *a* whereby this projection and consequently the rolling cylinder *f* are locked.

110 I claim:—

115 1. A rolling stamp with a locking device for automatically locking in the well known manner the counting mechanism at a predetermined number or value limit comprising in combination with the counting mechanism, a printing cylinder, a lever pivotably mounted between said counting mechanism and said printing cylinder, a fork at the upper end of said lever, an arm of the counting mechanism engaging with said fork, two laterally projecting arms of the lower part of said lever, a projection operated by the 120 125 130

rolling stamp designed to act upon the upper one of said arms for transmitting the movement of the printing cylinder to the counting mechanism, and a mechanism for locking said transmission means at the same time as the counting mechanism.

2. A rolling stamp with a locking device for automatically locking in the well known manner the counting mechanism at a predetermined number or value limit comprising in combination with the counting mechanism, a printing cylinder, a lever pivotably mounted between said counting mechanism and said printing cylinder, a fork at the upper end of said lever, an arm of the counting mechanism engaging with said fork, two laterally projecting arms of the lower part of said lever, a projection operated by the printing cylinder designed to act upon the upper one of said arms for transmitting the movement of the printing cylinder to the counting mechanism, a spring influenced angle lever pivotably mounted between said transmitting lever and the printing cylinder so that one of its arms is raised by said projection after the same has moved along the arm of said transmitting lever, whereby the second arm of said angle lever pushing upon said arm of the transmitting lever returns the same to the initial position, means for locking the counting device if a predetermined figure is reached, and means for locking said angle lever in the oscillated position so that the projection is prevented from operating said transmission lever.

3. A rolling stamp with a locking device for automatically locking in the well known manner the counting mechanism at a predetermined number or value limit comprising in combination with the counting mechanism, a printing cylinder, a lever pivotably mounted between said counting mechanism and said printing cylinder, a fork at the upper end of said lever, an arm of the counting mechanism engaging with said fork, two laterally projecting arms of the lower part of said lever, a catch operated by the printing cylinder designed to act upon the upper one of said arms for transmitting the movement of the printing cylinder to the counting mechanism, a spring influenced angle lever pivotably mounted between said transmitting lever and the printing cylinder so that one of its arms is raised by said projection after the same has moved along the arm of said transmitting lever whereby the second arm of said angle lever pushing upon said arm of the transmitting lever returns the same to the initial position, means for locking

the counting device if a predetermined figure is reached, a spring influenced axle below said counting mechanism, an angle lever upon one end of said axle the upper arm of said angle lever bearing normally against the bottom of the counting mechanism, a lever for operating the printing roller, an abutment on the lower part of said lever with which engages the lower arm of said angle lever for locking the projection if the counting device is stopped.

4. A rolling stamp with a locking device for automatically locking in the well known manner the counting mechanism at a predetermined number or value limit comprising in combination with the counting mechanism, a printing cylinder, a lever pivotably mounted between said counting mechanism and said printing cylinder, a fork at the upper end of said lever, an arm of the counting mechanism engaging with said fork, two laterally projecting arms of the lower part of said lever, a projection operated by the printing cylinder designed to act upon the upper one of said arms for transmitting the movement of the printing cylinder to the counting mechanism, a spring influenced angle lever pivotably mounted between said transmitting lever and the printing cylinder so that one of its arms is raised by said projection after the same has moved along the arm of said transmitting lever whereby the second arm of said angle lever pushing upon said arm of the transmitting lever returns the same to the initial position, a spring influenced hand adjustably mounted upon the top plate of the casing, a downwardly projecting point of said hand, a disk upon the upper figure disk of the counting device, spaced pins at the circumference of said disk arranged so that the end of said hand can engage between the same to lock the counting device if a determined figure has been reached, a spring influenced axle below said counting mechanism, an angle lever upon one end of said axle the upper arm of said angle lever bearing normally against the bottom of the counting mechanism, a lever for operating the printing cylinder, a bend in the lower part of said lever with which engages the lower arm of said angle lever for locking the projection if the counting device is stopped.

In testimony whereof I affix my signature in presence of two witnesses.
